INFANT FEEDING MEANS

Benjamin Alstadt and Harold Sappéy,
New York, N. Y.

Application July 9, 1951, Serial No. 235,792

14 Claims. (Cl. 128—252)

1 This invention relates to liquid feeding nipple constructions as used on infant nursing bottles, and more particularly is directed to improved nipple constructions and nipple accessories for serving, as in natural breast feeding, to minimize nervous tension that generally may be manifest by a so-called "colic condition" thereby providing for an improved method of infant feeding.

Among the objects of the invention is to generally improve feeding nipple constructions and methods of infant feeding of the character described and to provide nipple accessories for readily assembling with nipples of various types, sizes and shapes in use for the purpose of utilizing the improved feeding method, which constructions shall comprise few and simple multi-layers forming rugged structures capable of withstanding rough usage, which constructions and accessories shall be easy and cheap to manufacture, which shall be practically non-collapsible in use, which shall require in operation relatively low suction conditions, which constructions, accessories and method shall during feeding aid in continuously maintaining connection between the lips and nipple thereby more closely approximating natural breast feeding conditions, which shall be easy to keep in sanitary and hygienic condition, which shall be reliable in operation, which shall be adaptable to be conformed to various types of feeding bottles, and which constructions, accessories and method shall be practical and efficient to a high degree in use.

This application is a continuation in part of applicants' invention described and shown in Ser. No. 147,242 filed March 2, 1950 for Nursing Bottle Nipples, now Patent No. 2,582,950.

Other objects of the invention will in part be obvious and in part hereinafter pointed out.

The invention accordingly consists of features of constructions and method, combination of elements and arrangement of parts and steps in the method which will be exemplified in the constructions and method hereinafter described and of which the scope of the application will be indicated in the claims following.

In the accompanying drawing in which embodiment of the invention are shown,

Fig. 1 is a front elevational view of a multi-layer wall liquid feeding nipple constructed to embody the invention.

Figs. 2 and 3 are top and bottom plan views, respectively, of the improved nipple shown in Fig. 1 and showing respectively the outlet and

inlet ends of the spaced apart air passageways formed in the multi-layer wall thereof.

Fig. 4 is a sectional view taken on line 4—4 in Fig. 1 showing the lengths of the air passageways or ducts formation in the multi-layer wall.

Fig. 4a is a fragmentary sectional view showing a modified form of the nipple construction in which the inlet ends of the passageways or ducts are located in the plane of bottom surface of the nipple bead.

Fig. 5 is a sectional view taken on line 5—5 in Fig. 1 showing a cross section of a mid portion of said multi-layer wall.

Figs. 6 and 7 are front elevational and top plan views, respectively, of the improved nipple construction shown in Fig. 1 with the external layer sheath removed to show the molded rib on the inner nipple layer.

Fig. 8 is a sectional view similar to Fig. 5 showing a modified form of multi-layer wall construction in which the ribs are molded to the external layer sheath, and

Fig. 9 is a sectional view similar to Figs. 5 and 8 showing another modified form of multi-layer wall constructed with an intermediate corrugated layer between an inner and external layer sheath.

Referring in detail to the drawing, 20 denotes a nipple formed of a flexible material, such as gum or synthetic rubber or other suitable substances having elastic properties constructed as hereinafter described with a multi-layer wall structure embodying the invention.

Nipple 20 as seen from Figs. 1—7 may be a double wall or layer structure forming a teat or bulbous hollow head portion 21 extending from a double wall or layer structure forming sleeve or neck 22, the latter extending between said teat portion 21 and a hollow double wall or layer structure forming a base or breast portion 23. The double layer wall structure portions of said teat 21, neck 22 and breast 23 may comprise of integral teat, neck and breast parts 21a, 22a and 23a, respectively, of an inner sheath layer or liner, indicated generally at 20a; and a superimposed exterior ply layer or outer covering 20b of said double wall structure portions comprising integral teat, neck and breast parts 21b, 22b and 23b, respectively.

Inner teat part 21a may be a substantially hemispherical-shaped structure having one or more through-openings 21c to permit flowing of liquid from the interior of teat portion 21 therethrough and through aligned opening 21d provided in said outer covering teat part 21b and

positioned to register with said opening 21c. Said inner breast part 23a may terminate in a bottom end thickened peripheral rim or bead 23c for retaining nipple 20 on a mouth of a feeding bottle (not shown) in the well understood manner.

Said inner sheath layer or liner 20a may be formed to have extending along the length of the surface thereof facing outer covering 20b, spaced apart integrally formed ribs 20c which 10 serve in the assembly of outer covering 20b on inner liner 20a as partitions for elongated continuous air-passageways or conduits 24 formed to pass successively through teat portion 21, neck portion 22 and breast portion 23 as is clear from Figs. 1 to 7. Passageways 24 may each terminate in an end outlet 24b in teat portion 21 at a spaced distance from said opening 21d of teat part 21b, said nipple 20 having an end inlet 24a for each passageway 24 located just above the bead 23c as 20 is clear from Fig. 4.

Thus it is seen that said aligned through-openings 21c and 21d of inner and outer teat parts 21a and 21b, respectively, when assembled in register serve to permit the flow of liquid contents of the feeding bottle through the nipple 20 into a child's mouth in which said teat portion 21 is placed in the well known manner for feeding liquids from a bottle, and air-passageways 24 provide direct communication of said teat portion 21 with said aligned through-openings 21c and 21d in the child's mouth with the surrounding air independent of the contents of the nursing bottle and liquid flow therefrom.

Nipple 20 as above described and shown in Figs. 1-7 may thus be constructed by molding of a suitable rubber or plastic product having desirable properties with teat, neck and breast parts 21a, 22a and 23a, respectively, as integral inner sheath or liner 20a and with partition forming ribs 24 and said through-opening 21c, and also by molding of a like or different rubber or plastic product teat, neck and breast part 21b, 22b and 23b as integral outer covering 20b with through-opening 21d, and said passageway end outlets 24a and end inlets 24b.

Outer covering 20b may be molded to a size so as to stretchingly snug-fit against the partition forming ribs 20c on inner liner 20a thereby forming said air-passageways 24. If desired the lower edge portion 23d extending from breast part 23b of outer covering 20b may be extended to encircle bead 23c of said liner 20a so as to positively retain the outer covering 20b against accidental movement from proper assembly on said liner 20a.

A practical application of the invention may be carried out by simply mounting nipple 20 assembled as described above and shown in Figs. 1 to 7 on a feeding bottle containing a milk formula, water or any other feeding liquid and on inserting said nipple 20 into an infant's mouth whereby teat portion 21 having through-openings 21c and 21d, and said outlet ends 24a of air-passageways 24 are positioned within the mouth cavity, the infant's lips will close about nipple neck 22 in position against breast 23 with said passageway inlet ends 24b communicating with the free atmosphere. When sucking by the infant commences the liquid will flow from the bottle in an even stream through said through-openings simultaneously with atmospheric air flowing through passageways 24 into the mouth cavity. This flow of air between the atmosphere and mouth cavity is substantially free and unimpeded so that after the completion of each suck

there is sufficient air supplied to the mouth cavity for replacing the partial vacuum created within the bottle without requiring releasing the connection between the nipple 20 and the infant's lips.

When sufficient liquid flows into the throat to initiate a swallowing reflex, the liquid will pass down the esophagus and any excess air in the mouth cavity will be taken care of through the respiratory system.

In practicing the invention with nipple 20 in maintaining the above described communication of air between the free atmosphere and the infant's mouth cavity during sucking, the infant will be found to take liquid food from a bottle contentedly and in a relaxed mood so as to minimize often present nervous tension to which gastric disturbances and distress are attributed.

In Fig. 4a is shown a different disposition of end inlet 124a of air-passageway 124 with respect to the bead 23c of inner breast part 23a shown in Fig. 4. Here the partition forming ribs 120c are each extended to reach around the bead 23c and said passageway end inlets 124b located substantially in plane XX of the bead 23c instead of above the latter.

A modified form of nipple construction 30 embodying the invention is shown in Fig. 8 in which the multi-wall structure differs from that described above and shown in Figs. 1-7 in that partition forming ribs 30c of the improved nipple construction 30 may be molded as integral parts of outer covering 30b instead of part of the nipple inner liner 20a, and inner liner 30a is instead provided with an uninterrupted continuous smooth surface against which ribs 30c seat.

Nipple 30 otherwise may be constructed like nipple 20 to provide air-passageways 34 end inlets and outlets for said passageways 34 and aligned through-openings in register disposed in the same relative position as described above for nipple 20 and shown in Figs. 1-7.

Fig. 9 shows another modification of nipple construction 40 embodying the invention in which the multi-wall construction thereof differs from nipples 20 and 30 described above and shown in Figs. 1-8, in that a corrugated or like sectioned intermediate member 40c is used instead of the partition forming ribs 20c and 30c of nipples 20 and 30, respectively, and is inserted between smooth surfaced inner liner 40a and outer covering 40b.

Nipple construction 40 may also otherwise form an assembly structure with air-passageways 44, and end inlets and outlets for said air-passageways 44 and aligned through-openings in register disposed in the same relation as described above for nipple 20, and shown in Figs. 1-7. Intermediate member 40c may be made of suitably molded rubber or other plastic material having like desired properties.

It is to be noted, however, that in nipple constructions 20, 30 or 40, either the inner liners of each outer covering or intermediate member 40c of nipple 40 may selectively be made to have the same or different predetermined resilient properties to suit a wide range of use requirements.

The novel improved method of infant feeding embodying the invention will now be apparent and is seen to comprise the steps of feeding a liquid from a nursing bottle through nipple 20, 30 or 40 by mouth suction while simultaneously maintaining free communication of atmospheric air within the mouth cavity, that is, concurrently drawing air from the atmosphere outside the

mouth into the region of mouth suction within said cavity.

Nipples 30 and 40 will each operate in the same manner as described above for nipple 20 and it is to be understood that the various modifications in number and cross-sectional shapes and sizes of the air passageways may be utilized in any form of multi-layer nipples without departing from the scope of the invention.

It has been found that favorable results are obtained in the modifications shown when through-openings 21c, 21d are of the usual size; that is, so that an intermittent drip of liquid will take place when the bottle is inverted with said nipple opening or openings thereof below the liquid level in the bottle and the air passageways 24, 34 and 44 have a total effective diameter of about 1 mm. Where a plurality of passageways 24, 34 and 44 are provided on a nipple, each passageway having a correspondingly smaller diameter has been found to render satisfactory results.

It is thus seen that there are provided an improved method of infant feeding and liquid feeding nipple constructions in which the objects of the invention are achieved and which are well adapted to meet all conditions of practical use.

As various possible embodiments may be made in the above invention and as various changes might be made in the embodiments and method above set forth, it is understood that all the above matters herein set forth or shown in the accompanying drawings are to be interpreted as illustrative and not in a limiting sense.

Having thus described our invention, we claim as new and desire to secure by Letters Patent:

1. A nursing nipple of the character described comprising a multi-layer elastic tubular wall structure terminated by a perforated head for passing a flow of liquid from a bottle therethrough, said wall structure formed of superimposed layers having an elongated air conduit extending therebetween, said air conduit having an inlet located in the region of the perforated head and an outlet spaced therefrom both communicating with the exterior of the nipple, said conduit being partitioned off from said liquid flow within the tubular structure.

2. A nursing nipple having a head opening of the character described comprising a multi-layer tubular wall structure for drawing a liquid flow from a bottle through said opening, said wall structure of superimposed layers of elastic material formed with at least one elongated air passageway extending between said layers partitioned from said liquid flow within the nipple, said passageway having an inlet communicating with the atmosphere at an exterior side of nipple and outlet adjacent said nipple head opening.

3. A nursing nipple of the character described comprising a multi-layer tubular wall structure terminated by a perforated head for passing a flow of liquid from a bottle therethrough, and an elongated air conduit contained between the nipple structure layers having both an inlet and outlet communicating with the exterior of the nipple, said conduit outlet being located in the region of the perforated head.

4. An infant's nursing nipple having a hollow perforated head for drawing a liquid flow from a bottle therethrough comprising a multi-layer wall structure, an elongated air conduit formed to extend between said wall structure layers completely partitioned from said liquid flow communicating a region of said head within the in-

fant's mouth with the atmosphere external to the nipple when the latter is in suckling position.

5. A nursing nipple of the character described comprising an elastic multi-layer tubular wall structure terminated by a perforated sucking head for passing a flow of liquid from a bottle therethrough, one of said layers having a partition forming rib facing another layer to provide an elongated air conduit extending longitudinally between said layers, said air conduit having an outlet end in the nipple exterior region of said perforated sucking head and having an inlet end communicating the conduit with the exterior of the nipple when said sucking head is in a child's mouth.

6. A nursing nipple of the character described comprising a multi-layer structure having a perforated bulbous hollow teat portion, a tubular neck extending from said teat portion, said neck being interposed between the teat portion and a flexible walled hollow dome shaped breast, and spaced apart air-passageways extending longitudinally between adjacent layers of the nipple structure through wall portions of said breast, neck and teat portions, said air-passageways each having an inlet on said breast and outlet on said teat portion communicating an exterior side of the nipple teat portion when within the mouth in suckling position with the atmosphere external the mouth.

7. The nursing nipple defined in claim 6 including spaced apart partition forming ribs formed on one of said wall structure layers facing another layer through which said air-passageways extend.

8. An infant's nursing nipple having a multi-layer wall structure comprising perforated bulbous hollow head portion wherethrough a liquid flow passes, a tubular neck extending from said head portion interposed between the latter and a breast portion, an elongated air conduit formed between said wall structure layers completely partitioned from said liquid flow communicating a region of said head portion within the infant's mouth with the external atmosphere outside the infant's mouth when said nipple is in suckling position, said air conduit having an inlet end on the breast portion beyond the infant's lip sucking position and an outlet end in the region of said nipple perforated head portion.

9. The infant's nursing nipple defined in claim 8 in which said wall structure forming the elongated air conduit includes an intermediate corrugated layer inserted between two other layers.

10. The infant's nursing nipple defined in claim 8 in which said elongated air conduit is formed between layers of different rigidity to provide a single structure of predetermined elasticity.

11. A nursing nipple of the character described comprising a multi-layer structure having a perforated bulbous hollow teat portion, a tubular neck extending from said teat portion, said neck being interposed between the teat portion and a flexible walled hollow dome shaped breast, and an elongated air conduit extending between adjacent layers of said nipple structure having an end inlet on said breast, said conduit extending through layers of said tubular neck and terminating in an end outlet on said teat portion.

12. In an infant's feeding nipple, a multi-layer structure having a perforated bulbous hollow teat portion, an intermediate tubular neck and dome shaped breast portion, the latter terminating in means for mounting the nipple on the mouth of a feeding bottle to pass liquid flow from

the latter into the infant's mouth through said nipple when in suckling position, an air conduit formed between the layers of said structure communicating an end inlet thereof positioned on the nipple to lie exteriorly of the mouth when in said suckling position with an end outlet thereof positioned in the region of said teat portion within the mouth, said air conduit being partitioned off from said liquid flow through the nipple.

13. An infant's nursing nipple accessory for fitting over a nipple structure of conventional construction wherethrough a liquid flow passes comprising an elastic outer layer formed with a bulbous hollow teat portion, a tubular neck extending from said neck interposed between the teat portion and a flexible walled hollow breast, said layer being shaped and sized to conform to said nipple structure, a rib integrally extending along an interior surface of said layer for abutting the nipple structure and forming an elongated air conduit therebetween completely partitioned from said liquid flow, said air conduit having an inlet end on said breast and an outlet on the teat portion thereof for communicating a region of said teat portion within the infant's mouth with the external atmosphere outside the infant's mouth when the nipple structure is fitted with said accessory.

14. An infant's nursing accessory for fitting over a nipple structure of conventional construction wherethrough a liquid flow passes comprising an elastic outer layer formed with a bulbous hollow teat portion, a tubular neck extending from said teat portion, said neck interposed between the teat portion and a flexible walled hollow breast, said layer being shaped and sized to conform to said nipple structure with an intermediate corrugated spacer therebetween to provide an elongated air conduit completely partitioned from said liquid flow, said air conduit having an inlet end on said breast and an outlet on the teat portion thereof for communicating a region of said teat portion within the infant's mouth with the external atmosphere outside the infant's mouth when the nipple structure is fitted with said accessory.
